UNITED STATES PATENT OFFICE.

MICHAEL S. BASSITY, OF NEW YORK, N. Y.

EMBROIDERING DEVICE.

Application filed October 11, 1920, Serial No. 416,269. Renewed April 14, 1925.

To all whom it may concern:

Be it known that I, MICHAEL S. BASSITY, a citizen of Russia, and resident of New York, in the county of New York and State 5 of New York, have invented a certain new and useful Improvement in Embroidering Devices, of which the following is a specification.

My invention relates to embroidering devices and has particular reference to portable tools adapted for inserting thread or string loops into a fabric.

My invention has for an object to provide a device of the character above indicated 15 capable of operation with one hand, and characterized by simplicity of construction.

My invention is more fully described in the following specification, and illustrated in the accompanying drawings in which:—

20 Fig. 1 is a longitudinal sectional view of my improved device.

Fig. 2 is a similar view, but showing the needle engaged with a fabric.

Fig. 3 is a front elevational view of the 25 device.

Fig. 4 is a detail front elevation of the outer sleeve.

Fig. 5 is a side elevation of the presser foot.

30 Fig. 6 is a front view thereof.

Fig. 7 is a horizontal sectional view of the device, taken on the line 7—7 of Fig. 1, certain parts being omitted.

Referring now to Figs. 1 to 7 my improved 35 device comprises a bar 20 fixed in the lower end of a tube 11. A space is provided between one side of the bar and the adjacent wall of the tube to receive a rigid strap 21 having a horizontally projected offset 30 at 40 its lower end, these parts being hereinafter referred to as the presser foot. The strap 21 is secured adjustably in place by means of a headed screw 33 passing freely through a suitable aperture in the tube 11 and 45 through a vertical slot 31 in the strap, and threaded into the bar 20, the wall of tube 11 possessing sufficient resiliency to cause it to bind on the strap when the head of the screw is tightened against such wall.

50 A needle 2 of ordinary construction is fixed at its butt end in a suitable socket in the bar 20 by means of a set screw 3, the needle projecting downwardly from said bar and passing through an aperture 62 in 55 the presser foot element 30.

Loosely surrounding the tube 11 is a sleeve

12 which has limited sliding movement longitudinally thereof, this sleeve having projected downwardly from its lower end, at one side thereof, an integral tongue 14 having an outturned lip 16 at its lower end. This tongue extends loosely through a suitable slot in a lateral offset 60 formed on the lower portion of the bar 20, and is formed at its lower end with an aperture 17 through 60 which the thread is passed. The tongue 14 is somewhat longer than said offset; the end of the sleeve 12 and the lip 16 on the tongue being adapted to engage upper and lower ends respectively of said offset to limit the 65 sliding movement of the sleeve.

My improved device may be operated by one hand only, the thread being alternately caught between the lip 16 and the base of offset 60 as the device is moved upward, and 70 freed from the grip of said parts as the sleeve is moved downward, forming a row of loops 36 in the fabric, as indicated in Fig. 2.

As indicated at 28 I may provide an expansion spring in the upper end of the tube 80 which bears at one end on an offset on the strap 21 and at its opposite end on a cap 13 on the sleeve 12 and automatically returns the latter to raised position. 85

While I have illustrated and described a preferred embodiment of my invention it is to be understood that I do not limit myself to the precise construction herein disclosed and various changes and modifications may 90 be made therein without departing from the spirit and scope of the invention as defined in the appended claims.

I claim as my invention:

1. An embroidering device comprising a 95 bar, a needle and a presser-foot fixed to said bar, a sleeve slidable on said bar, and co-operating thread-gripping elements on said sleeve and bar adapted to grip the thread when the sleeve is moved upwardly on the 100 bar, the thread gripping element on the sleeve comprising a tongue projected downwardly from one side thereof and having a lip formed on its lower end adapted to engage the bottom of the said bar, said tongue 105 having a thread receiving aperture in its lower end.

2. An embroidering device comprising a 110 bar, a needle and a presser-foot fixed to said bar, a sleeve slidable on said bar, and co-operating thread-gripping elements on said sleeve and bar adapted to grip the thread

- when the sleeve is moved upwardly on the bar, and a spring bearing between said sleeve and bar to move the former upwardly.
3. An embroidering device comprising a bar, a tube fixed to said bar and projecting upwardly therefrom, a presser-foot element in the form of a longitudinally slotted strap engaging one face of the bar and projecting freely upward in the said tube at one side thereof, a set screw passing through the slot in said strap and securing said strap to said bar, said strap having a horizontally projected offset at its lower end formed with an aperture, a needle fixed in said bar and extending through said aperture, a laterally

projected offset on the lower end of said bar, a sleeve freely surrounding said bar and tube above said offset on the bar, a tongue on said sleeve extending downwardly through said last offset and having a lip on its lower end, said tongue being formed at its lower end with a thread receiving aperture, and a spring in said tube and bearing between said bar and sleeve to raise the latter.

Signed at New York in the county of New York and State of New York this 30th day of September A. D. 1920.

MICHAEL S. BASSITY.
